Inventor:

James Budd

United States Patent Office.

JAMES BUDD, OF PITTSFORD, NEW YORK, ASSIGNOR TO "BUDD AND BRIGGS."

Letters Patent No. 64,193, dated April 30, 1867.

GATE.

The Schedule referred to in these Letters Patent and making part of the same.

TO ALL WHOM IT MAY CONCERN:

Be it known that I, JAMES BUDD, of Pittsford, in the county of Monroe, and State of New York, have invented a new and useful Mode of Opening and Closing Gates or Doors by means of Double-Action Lever; and I do hereby declare that the following is a full and exact description thereof, reference being had to the accompanying drawing, and to the letters of reference marked thereon.

Figure 1 represents a perspective view of my double-action-lever gate or door.

Figure 2 represents a cross-section of the rollers, and mode of hanging my gate or door.

The nature of my invention consists in attaching to any double gate or pair of doors four or more rollers *g*, either on top or bottom. I also attach a double-action lever, *a b b*, and a horizontal bar, *c*, running at right angles with gate or door, for the purpose of opening or shutting the door or gate.

To enable others to make and use my invention, I will proceed to describe its construction and operation.

I construct my gate by erecting a frame of four upright pieces, *o o o o*, to which a plank, *p*, is nailed on top. *i i* is a narrow board of suitable thickness, nailed on upright pieces *o o o o*, leaving a space between the upper edge of board *i i* and top piece *p*, as seen in drawing. *e e e e* are either short or long strips of boards, to which the gate or door is fastened, and on which the gate or door is hung. The upper ends of upright strips *e e* are united by a short strip of board, *f*, on one side, and on the opposite side the rollers *g g* are fastened. These rollers *g g* run on the upper edge of board *i i*, without any extra track. The upright pieces *e e e e* are held in their places by a piece of board, *h h*, nailed on board *i i* in such a way as to leave space enough for the upright pieces *e e e e* to slide freely to and fro, when the lever *a* is worked. *c c* is a horizontal bar running at right angles with the door or gate, and high enough to admit of the passage of a load of hay when necessary. The bar *c c* also extends from twelve to fourteen feet out each way from the gate or door, and passes through the stanchion *l*, at which point is the fulcrum. To this horizontal bar *c c* are attached three double-action levers: first, the main lever *a*, with levers *b b* attached; second and third, the double-action levers *d d*. *b b* are two levers attached to main lever *a* and to the centre of strips *f f*, for the purpose of opening the door or gate. When the double-action lever *d* is worked, the points or pins *g g* attach the levers *b b* to the strips *f f*, and which form a horizontal line with the fulcrum at *l*, will move on the line thus formed, and in so doing open or close the gate or door; and for this purpose it is necessary that they should move in this horizontal line. The two extreme ends of bar *c c* pass through the arms *r r*, of the upright *m m*, for the purpose of support, and to keep the same in a horizontal position. At either end of the bar *c c* is attached a double-action lever, *d*, to which the cords *n n* are hung, for the purpose of opening or closing the gate or door at will, and that those passing through in carriages may open or close the gate or door without leaving the carriage. *k k* are narrow strips of boards, which are nailed to upright pieces *e e e e*, for the purpose of preventing the gates or doors from tipping up. The centre bar *c c*, with the levers *a* and *b b*, can be placed at either side of the door or gate, or under ground, where they can be operated in the same manner and for the same purpose.

What I claim as my invention, and desire to secure by Letters Patent, is—

The combination of the double-action lever *a* with the levers *b b*, double-action levers *d d*, horizontal bar *c*, strips *e e e e* and *f f*, guiding boards *i* and *h*, also posts *m m* with arms *r r*, the whole operating substantially in the manner described and for the purpose set forth.

JAMES BUDD.
